UNITED STATES PATENT OFFICE.

ROBERT HARDIE, OF ASHFIELD, NEAR SYDNEY, NEW SOUTH WALES, AUSTRALIA.

DENTAL ARTICULATOR.

1,102,741.

Specification of Letters Patent.

Patented July 7, 1914.

Application filed February 4, 1914. Serial No. 816,421.

To all whom it may concern:

Be it known that I, ROBERT HARDIE, a subject of the King of Great Britain, residing at No. 8 Bland street, Ashfield, near Sydney, in the State of New South Wales and Commonwealth of Australia, brass finisher, have invented new and useful Improvements in Dental Articulators, of which the following is a specification.

10 This invention relates to dental articulators which have adjustable parts and it has been specially devised in order to provide an improved dental articulator of simplified and cheap construction in which 15 molds for artificial dentures may be readily affixed in working position and may be easily and quickly removed therefrom without being broken or injured and in which also the relative position of said molds may be 20 more expeditiously adjusted at the will of the worker than heretofore.

According to these improvements a vertical distance pillar is formed integral with or fast to a fixed lower arm and it has a 25 central hole or slot extending from the top through the greater part of its height to slidably receive a vertical stem whose height is adjustably fixed by means of a set screw. This stem carries on its upper end the hinged 30 upper arm resting upon the upper end of a screw pin passing through a lug on the inner side of said distance pillar and having a jam nut abutting thereon. The upper movable arm is constructed of two leaves 35 the lower one of which is hinged to the upper part of the beforementioned slidably adjustable stem of the vertical distance pillar while the upper leaf is horizontally adjustable in relation thereto by means of longitudinal slot and a clamping screw. Each 40 arm is spread at its free end and has inwardly directed lugs which for the upper arm are in combination with a movable clamping piece which is carried upon the 45 arm in a slot through both leaves thereof and is operable by means of a screwed stem passing through a female thread in a lug thereon and having abutments against another similar lug by collars on said stem 50 and which for the lower fixed arm are in combination with a clamp piece fast on a screwed stem passing through the distance pillar and having jam nuts on each face thereof. But in order that this invention 55 may be easily carried into effect it will now be described with reference to the drawings

accompanying and forming part of this complete specification in which

Figure 1 is a perspective view and Fig. 2 a longitudinally central sectional elevation 60 of dental articulator embodying these present improvements.

The distance pillar 3 carries one end of fixed arm 4 on its lower end and it has a central hole or slot 5 in it to receive vertically slidable stem 6 with or without a feather 7 and adapted to be secured in position by a set screw 8. A lug 9 is provided on the inner side of pillar 3 and adjustable screwed pin 10 having jam nut 11 projects 70 upwardly therethrough and forms a rest for the hinged upper arm consisting of two leaves 13 and 14 the lower one (13) of which is hinged to said vertically adjustable stem 6 while on it the upper one (14) is 75 longitudinally horizontally adjustable by means of slot 15 and clamp screw 16. Each arm is spread at its free end and has two inwardly directed lugs 17. Upon the upper arm 12 the movable clamping piece 18 has 80 a lug 19 extending through slot 20 and having a female screw adapted to receive a screwed stem 21 which passes through lug 22 on upper leaf 14 and has abutment collars 23 on each side thereof and a milled head 24 on its end. The lower fixed arm supports a similar clamp piece 18 upon a 85 screwed stem 26 which passes loosely through orifice 27 in pillar 3 and has jam nuts 28 on each side thereof.

In use a denture mold is placed in position on each arm between the lugs or stops 17 and clamp piece 18 and firmly fixed therein by means of screwed stem 21 while the upper leaf 14 of the upper arm is adjusted 90 by means of clamping screw 16 and slot 15 to properly position the molds horizontally relative one to the other. The slidable stem 6 in the pillar 3 and abutment stem 10 are 95 then adjusted that when the hinged arm is in lowermost position the molds meet at the correct angle of articulation.

What I claim as my invention, and desire to secure by Letters Patent is:—

1. In dental articulators the combination 105 with a hinged arm spread at its free end and having inwardly directed lugs with a movable clamping piece of a lug on said clamping piece in a slot through said arm and having a female screw a screwed stem 110 passing through said female screw and having two collars and a lug upon the arm to

form abutments for said collars substantially as herein described and explained.

2. In dental articulators the combination with a fixed lower arm spread at its free end and having inwardly directed lugs of a clamping piece carried on a screwed stem passing through the fixed support of said arm and adapted to be held by jam nuts substantially as herein described and explained.

3. In dental articulators, in combination, a distance pillar, a fixed lower arm carried thereby, said arm being spread at its free end and having inwardly directed lugs, a threaded stem passing through said pillar,

means for holding said stem in position, a clamping piece carried by said stem, a hinged arm supported upon said pillar, said arm being spread at its free end and having inwardly directed lugs, a clamping piece movably supported on said hinged arm, and means carried by said hinged arm for moving said last mentioned clamping piece.

In testimony whereof I have signed my name to this specification in the presence of two subscribing witnesses.

ROBERT HARDIE.
